Patented Sept. 10, 1918.

UNITED STATES PATENT OFFICE.

EDWARD JOOS, OF ST. LOUIS, MISSOURI.

TOY.

1,278,674.

Specification of Letters Patent. Patented Sept. 10, 1918.

Application filed January 24, 1918. Serial No. 213,593.

To all whom it may concern:

Be it known that I, EDWARD JOOS, a citizen of the United States, residing at the city of St. Louis, in the State of Missouri, have invented certain new and useful Improvements in Toys, of which the following is a specification.

This invention is a toy in which the function of two varieties of amusement are found, the primary form being adapted to hold attention and the second being adapted to produce surprise while the attention is concentrated upon said first form of amusement.

The game played with this toy in the said first form of amusement may, if desired, be called "Hanging the Hun" but other names will be equally suitable.

In the accompanying drawings forming part of this specification, in which like numbers of reference denote like parts wherever they occur,

Figure 1 is a perspective view;

Fig. 2 is a vertical sectional view;

Fig. 3 is a vertical sectional view illustrating the position and action of the parts when the above-mentioned second form of amusement is utilized, while Figs. 1 and 2 illustrate the use of the device in the first-mentioned form of amusement.

The gibbet 1 is provided with a suitable noose ring or loop 2, preferably formed of wire or the like, and the upright 3 of the gibbet 1 is inserted in a base or block 4.

A nipple or mouth-piece 5 containing a passage 6 is inserted in base 4 and extends into the recess 7 in the central part of base 4, beyond the point of insertion of vertical tube or member 8 which contains passage 9.

The member 8 and the mouth-piece 5 are substantially at a right angle to each other, as are also the passage 9 and the passage 6. The inner end of the passage 6 terminates in a short passage 10 which is at a right angle to passage 6 but in alignment with passage 9.

Thus it will be seen that when air is blown in passage 6 through mouth-piece 5, when the parts are in the position shown in Fig. 2, the air will pass in the direction of the arrows in Fig. 2 and blow against the ball 11 of light material, such for instance as cork, and will blow the said aerial projectile or ball into sundry positions above member 8 and more or less adjacent to noose 2. If the player is lucky or skilful, continued blowing will cause ball 11 to go so near to

noose 2 as to hang the hook 12 over or in loop 2, which of course constitutes success in the game. In Fig. 1 ball 11 is shown in full lines in initial position like that in Fig. 2 and is shown in the upper part of Fig. 1 in dotted lines in two later positions, the dotted figure to the right showing the same in final or hooked position while the dotted figure to the left shows the ball 11 in one of many positions that the same occupies while the player is trying to cause hook 12 to enter and hang in loop 2.

The diverging lines will be recognized as indicating the air-blast that causes the ball 11 to rise from the initial position toward loop 2 and which also keeps the same actuated toward many intermediate positions before the successful finale is reached.

If desired, the ball 11 can be decorated with a picture of any public character who is the object of obloquy or in any other suitable manner.

In playing with this toy, sometimes the ball 11 is quickly hooked into loop 2 and on other occasions half an hour's effort may be unsuccessful.

At rest, ball 11 is seated on the mouth 13 of passage 9 and is kept measurably secure in such seat by a tail, such as the projecting wire rod or the like, 14, that extends downwardly in passage 9 and which serves as a weight that keeps hook 12 constantly on the upper side of the ball while the ball is being agitated as indicated in Fig. 1. As shown in Fig. 2, the hook 12 and the tail 14 are preferably integral and formed from a single piece of wire or rod.

The game as hereinbefore described secures such close attention from the player that he is likely to be unobservant of the opening 15 at the end of passage 16 in the gibbet 1 and upright 3 and the larger air passage 17 in base 4. Anyone acquainted with the toy can at any suitable time or under any plausible pretext, find an opportunity, without attracting attention, to turn the mouth-piece 5 from the position shown in Fig. 2 to that shown in Fig. 3, in which passage 10 no longer communicates with passage 9, but opens directly into passage 17 in which is concealed a quantity of flour, charcoal or the like. The player resumes his endeavor to secure the hook 12 in loop 2 and blows with his previous vigor, and to his discomfiture and the amusement of those around him, receives the blast of flour 19, or the like, in his face.

To load this pulverulent material in the passage 17 the mouth-piece 5 may be removed from the base 4 which allows of its easy introduction through opening 20.

5 The device can be easily made of wood, but other material can be used. The uprights 3 and 8 are preferably fixed with reasonable security in base 4. The mouth-piece 5 may also be made irremovable therefrom, though necessarily revoluble in order to change the direction of opening of passage 10. Other means for loading the flour, etc., into passage 17 may be provided. It will be noticed that the opening 15 from 10 passage 16 is slanted in the direction of the person using the mouth-piece 5 when playing with the toy.

Having thus described this invention, I hereby reserve the benefit of all changes in 20 form, arrangement, order, or use of parts, as it is evident that many minor changes may be made therein without departing from the spirit of this invention or the scope of the following claims.

25 I claim:

1. A toy comprising a base, a support, a loop depending from the said support, an air-passage, and a projectile having a hook adapted in the flight of the projectile to catch on the said loop, so as to suspend the projectile therefrom.

2. A toy comprising a support, a noose, a projectile adapted to be caught by the said noose, and an air conduit comprising a hollow mouth-piece and a tube upon which the said projectile is adapted to seat when at rest, the said mouth-piece being revoluble and adapted to direct air blown through the same either toward the said projectile or 40 away therefrom, a reservoir adapted to contain comminuted material, an air-passage leading therefrom to a point higher than the said mouth-piece, and the said mouth-piece communicating with the said reservoir when 45 not in communication with the said projectile.

3. A toy comprising a support, a noose, a projectile adapted to be caught by the said noose, and an air conduit comprising a hollow mouth-piece and a tube upon which the said projectile is adapted to seat when at rest, the said mouth-piece being revoluble and adapted to direct air blown through the same either toward the said projectile or away 55 therefrom, a reservoir adapted to contain comminuted material, an air passage leading therefrom to a point adapted to the user's discomfort when using the mouth-piece.

4. A toy comprising a base having a chamber therein and three tubular members leading out of the said base, one of which perennially communicates with the said chamber and another of which is adapted to

establish communication therewith and the third of which is disconnected with the said chamber, the said second-mentioned communicating member being adapted alternately to communicate with the said chamber and with the said third-mentioned member.

5. A toy comprising a base having a chamber therein and three tubular members leading out of the said base, one of which perennially communicates with the said chamber and another of which is adapted to establish communication therewith and the third of which is disconnected with the said chamber, the said second-mentioned communicating member being adapted alternately to communicate with the said chamber and with the said third-mentioned member and a projectile normally seated upon the said third-mentioned member.

6. A toy comprising a base having a chamber therein and three tubular members leading out of the said base, one of which perennially communicates with the said chamber and another of which is adapted to establish communication therewith and the third of which is disconnected with the said chamber, the said second-mentioned communicating member being adapted alternately to communicate with the said chamber and with the said third-mentioned member, and a projectile normally seated upon the said third-mentioned member, the said first, second, and third-mentioned members each containing an air-passage.

7. In a toy, the combination, with a pneumatically-propelled projectile carrying a hook, of a member arranged in the path of flight of said projectile and adapted to be caught by said hook, and means carried by said projectile for maintaining the hook in advance of the projectile in the flight of the latter.

8. In a toy, the combination, with a pneumatically-propelled projectile carrying a hook, of a member arranged in the path of flight of said projectile and adapted to be caught by said hook, and a tail, constituting a weight, carried by said projectile diametrically opposite said hook.

9. In a toy, the combination, with a pneumatically-propelled projectile, of a member carried by and projecting at both ends from said projectile, one of said projecting portions being bent to form a hook and the other projecting portion constituting a tail, and a target disposed in the path of flight of said projectile and adapted to be caught by said hook.

In testimony whereof I hereunto affix my signature.

EDWARD JOOS,
